UNITED STATES PATENT OFFICE

ANTHONY M. MULDOON, OF ENGLISHTOWN, NEW JERSEY

RUG

Application filed November 30, 1931. Serial No. 578,021.

This invention relates to the art of weaving tufted pile rugs or other fabrics and more particularly to an improved rug that shows the pattern or design on the back of the rug as well as on the face thereof, and the method of weaving the same.

Heretofore rugs of the so-called "oriental" type have been made that show the design on the back as well as the face of the rug but these have proven unsatisfactory in practice for various reasons. In all of these rugs, with which applicant is aware, the tuft bends or loops which form the pattern on the back also serve to form the wearing surface of the rug and of course after a time the design wears off. This type of rug also necessitates duplicating of the weave on both sides of the rug with consequent use of considerable quantity of material making the cost of such rugs considerable. Applicant is aware of other attempts to weave a rug of this character such as carrying the looped portions of the tufts to the back of the rug and extending or bulging the looped portion laterally. Such looped portions and lateral extensions in these rugs also form the wearing surface and present a very loose weave and soon become displaced and the design disappears.

It is a primary object of my present invention to provide a rug on an Axminster loom that shows the pattern or design on the back as well as on the face of the rug. Another object is to provide such a rug in which the pattern or design that appears on the back of the rug does not form the wearing surface thereof. Still another object is to provide such a rug in which there is a substantial body to the fabric. A further object is to provide a rug that has an attractive back portion. A further object is to provide a rug that is simple in construction and economical to manufacture. A still further object is to provide a novel method of weaving a tufted pile fabric wherein the tuft bends are visible on the back of the rug but are protected from wear by the wefts and binders.

My invention will be better understood from the description thereof to follow taken

in connection with the accompanying drawing in which—

Figure 1 is a face view of an improved rug woven by my present invention.

Figure 2 is a view of the back of the same rug.

Figure 3 is an enlarged sectional view with the fabric spread apart to show the relative position of the tufts, wefts and warps in the rug.

Figure 4 is a sectional view showing the fabric tightly woven.

With reference to the drawing, my improved rug 5 has the pattern or design represented by a star 6 on the face 7 as well as on the back 8 thereof.

The rug 5 comprises or is formed of parallel rows of tufted pile, each row consisting of a number of tufts positioned side by side and looped about a shot of weft. The face 7 comprises the free ends of the tufts 9 after they are looped about the first shot of weft indicated as 10. The tufts 9 are of different colors, at least four different colors being possible with my improved rug, and are arranged in the rug to form a pattern, such as the star 6, or any other desired pattern.

My improved rug comprises the ordinary three shot weave, the first shot being indicated at 10, the second shot being indicated at 11, and the third shot being indicated at 12. Passing between these shots in a straight direction are the warp threads or stuffers 13 and 14; and interwoven between and around said shots are two more chain or binder warp threads indicated at 15 and 16. Looped around the first shot 10 are the tufts 9 with their free ends extending straight upwardly and their roots or bends below the stuffer 14. These tufts are made of wool yarn or other suitable material and may be of four different colors.

In the ordinary three shot rug the tuft bends 17 are hidden behind the lowermost shot 12 and only the binders and wefts are seen at the back of the rug. In my improved rug, these tuft bends 17 are positioned to one side of the lowermost shot 12 and are visible at the rear of the rug. These tufts are so woven in the fabric that their lowermost

portion is slightly above the lowermost portion of the shot 12 and the warp threads 15 and 16 so that these lowermost portions of the said shot 12 and threads 15 and 16 form 5 the wearing surface of the rug. By reason of this construction, the tuft bends are visible and are also protected from wear.

In the ordinary three shot rug, there are only three warp threads, two usually passing 10 straight through the shots and corresponding to stuffers 13 and 14, and another and third interwoven between the shots. In my improved rug, interweaving the warp thread 15 as aforesaid prevents the shot 10 from 15 being positioned directly above the lowermost shot 12. Interweaving the warp thread 16 as aforesaid prevents the uppermost shot 11 from being carried over and being positioned above the first shot or shot 10, and also 20 prevents said shot 11 from bending the tufts 9 laterally. The addition of an extra warp thread interwoven as aforesaid also helps to fill the fabric as will be understood.

I claim:

25 1. A tufted pile rug woven with three shots of weft comprising two series of stuffer warps extending substantially straight through the fabric in parallel planes, the first shot of weft lying between both stuffer warps, 30 the second shot of weft lying above the stuffer warps, the third shot of weft lying below both stuffer warps, a binder warp interwoven about the three shots of weft and passing across and above the first shot, a second 35 binder warp interwoven about the three shots of weft and passing across and below the first shot of weft, and tufts looped about the first shot of weft having bights positioned between the second and third shots of weft 40 whereby said bights are exposed and the same pattern shows both upon the face and back of the rug.

2. A tufted pile rug comprising three sets of weft threads interwoven with two sets of stuffer warps and two sets of chain warps, the three sets of weft threads being arranged in upper, intermediate and lower planes, and pile tufts, said pile tufts being looped around the weft threads in the intermediate 45 plane, one set of the stuffer warps extending between the weft threads of the upper plane and the weft threads of the intermediate plane and the other set of stuffer warps extending between the weft threads of the intermediate plane and the weft threads of the bottom plane, one set of chain warps extending over the weft threads in the upper plane and underneath the weft threads in 50 the other two planes and the other set of chain warps extending over the weft threads in the intermediate plane and under the weft threads in the lower plane whereby the pile tufts are held on their respective weft 55 threads between adjacent weft threads in 60 65

the upper plane with their bights visible at the back of the rug.

3. A tufted pile rug comprising three sets of weft threads interwoven with two sets of stuffer warps and two sets of chain warps, the three sets of weft threads being arranged in upper, intermediate and lower planes, and pile tufts, said pile tufts being looped around the weft threads in the intermediate plane, one set of the stuffer warps 70 extending between the weft threads of the upper plane and the weft threads of the intermediate plane and the other set of stuffer warps extending between the weft threads of the intermediate plane and the weft threads of the bottom plane, one set of chain warps extending over the weft threads in the upper plane and underneath the weft threads in the other two planes and the other set of chain warps extending over the wefts 75 in the intermediate and upper planes and under the wefts in the lower plane, the chain warps being arranged to lock the loops of the pile tufts between the weft threads of the upper and lower planes and between the adjacent weft threads so that the pattern is visible from the back.

4. A tufted pile rug comprising three sets of weft threads interwoven with two sets of stuffer warps and two sets of binder warps, the three sets of weft threads being arranged in upper, intermediate and lower layers, and pile tufts looped around the weft threads in the intermediate layer, one set of stuffer warps extending between the weft threads of the upper layer and the weft threads of the intermediate layer, the other set of stuffer warps extending between the weft threads of the intermediate layer and the weft threads of the lower layer, binder 90 warps passing respectively above and below the weft threads of the intermediate layer 100 to hold said weft threads and the attached pile tufts in position laterally and vertically between the adjacent upper and lower weft threads, some of the binder warps passing below the lower weft threads and some of the binder warps passing above the upper weft threads, the bights of the pile tufts being visible at the back of the rug.

5. A tufted pile rug comprising three sets of weft threads interwoven with two sets of stuffer warps and two sets of chain warps, the three sets of weft threads being arranged in upper, intermediate and lower layers, and pile tufts looped around the weft threads in the intermediate layer, one set of the stuffer warps extending between the weft threads of the upper layer and the weft threads of the intermediate layer and the other set of stuffer warps extending between the weft threads of the intermediate layer and the weft threads of the bottom layer, one set of chain warps passing successively over weft 110 threads in the upper layer, then over weft 115 120 125 130

threads in the intermediate layer, then under weft threads in the lower layer and so successively over and under succeeding weft threads, and the other set of chain warps 5 passing successively over weft threads in the upper layer, then beneath the next weft threads in the intermediate layer, then beneath the next weft threads in the bottom layer, and so successively over and under

the succeeding weft threads whereby each pile loop is held on a weft thread in the intermediate layer and between two weft threads in the upper layer and the bight of each loop is visible at the back between successive weft threads in the lower layer.

In testimony whereof, I hereunto affix my signature.

ANTHONY M. MULDOON.
